UNITED STATES PATENT OFFICE

2,116,639

METAL THREADING APPARATUS

Edward J. Protin, Charleroi, Pa., assignor to Pittsburgh Steel Company, Pittsburgh, Pa., a corporation of Pennsylvania

Application October 14, 1936, Serial No. 105,539

4 Claims. (Cl. 10—105)

My invention relates to threading devices for pipes and the like, and more particularly to chuck apparatus used in connection therewith.

One object of my invention is to provide an improved manner of aligning and gripping a pipe or the like in an externally gripping chuck, relative to threading tools.

Another object of my invention is to provide in a chuck apparatus which is movable toward threading dies and which has a range of rapid traveling movement and a range of slower advancing movement, means for automatically stopping the rapid travel of the chuck when it reaches a predetermined position with relation to the threading device.

A further object of my invention is to provide in a chuck carriage of the character referred to, mechanism for mechanically advancing the chuck apparatus, and mechanism for manually advancing the same, in combination with means for automatically disconnecting the manual advancing means when the mechanically actuated advancing means is in operative position.

Still another object of my invention is to provide in traveling chuck apparatus of the character referred to, a stop gauge for engagement by the end of a pipe which is inserted in the chuck apparatus preliminary to a threading operation, the stop device being automatically movable out of the path of the pipe as it is advanced to a threading die and being automatically restored to operative position upon withdrawal of the pipe from the threading tool.

Another object of my invention is to provide a chuck apparatus having a set of chuck jaws for aligning a pipe, or the like, and a second set of chuck jaws for holding the pipe against the torque of threading tools, the second-named jaws being so supported as to permit of their automatic accommodation to the aligned position of the pipe.

In the accompanying drawings, Figure 1 is a front elevational view of the chuck apparatus and the threading machine; Fig. 2 is a rear elevational view thereof; Fig. 3 is an end elevational view of the chuck apparatus; Fig. 4 is a view taken on the line IV—IV of Fig. 1; Fig. 5 is a view taken on the line V—V of Fig. 4; Fig. 6 is an enlarged view looking in the direction of the arrows VI—VI of Fig. 2, partly in section; Fig. 7 is an enlarged elevational view of a portion of the apparatus of Fig. 1; Fig. 8 is a view taken on the line VIII—VIII of Fig. 7; Fig. 9 is a view taken on the line IX—IX of Fig. 7; Fig. 10 is a

view on an enlarged scale taken on the line X—X of Fig. 1; Fig. 11 is a view taken on the line XI—XI of Fig. 10; Fig. 12 is a plan view, partly in section, of the carriage for supporting the chuck apparatus; Fig. 13 is a view taken on the line XIII—XIII of Fig. 12, and Fig. 14 is a view taken on the line XIV—XIV of Fig. 12.

Referring first to Figs. 1 to 4, I show a threading machine A and chuck apparatus B for moving the pipe into position to have threads cut thereon by the threading machine. The threading machine per se does not constitute a part of my invention, but may be of any various known types and will, therefore, be described here in somewhat general terms.

The threading machine is mounted on a base 10 and comprises a casing or housing 11 within which is mounted a spindle 12 secured within a supporting sleeve 13 (Fig. 11), the sleeve being rotatable in bearings 14 and 15, formed in the end walls of the casing. The spindle 12 has a flared end 16 to which is bolted a head or holder 18 within which are mounted threading chasers or dies 18a, commonly termed receding chaser dies, which are radially movable toward and from threading position. A motor 19 (Fig. 1) is mounted on the casing 11 and drives a shaft 20 on which are mounted pinions 21 and 22 with which gear wheels 23 and 24 can be respectively brought into engagement after the manner of ordinary change-speed mechanisms. The gear wheels 23 and 24 are mounted upon a shaft 25 that also carries gear wheels 26, which mesh with gear wheels 27 that are mounted on a shaft 28. The shaft 28 carries a pinion 29 which drives a ring gear 30 that is secured to the sleeve 13, which sleeve is in turn keyed to the spindle 12. The driving connections just described serve to rotate the threading head 18.

The chuck apparatus includes a housing 32 which is mounted upon a carriage 33 that is supported upon slideways 34 which are carried by the base 10, whereby the carriage can be moved toward and from the threading mechanism in a manner to be hereinafter described.

A pipe-gripping chuck 35 and a pipe-aligning chuck 36 are mounted within the casing 32 and are of somewhat similar structure. The pipe-aligning chuck 36 includes three jaws 37 which are movable radially of the chuck body 38, in suitable guideways 38a formed therein, the chuck body 38 being an integral part of the casing 32.

The jaws 37 are radially movable by means of screws 39 which have threaded engagement therewith, and each of which carries a bevel

45

50

55

pinion 40 that is secured to its screw shaft 39. At its outer end, the screw shaft extends through a bearing bushing 41, a thrust bearing 42 being interposed between the pinion 40 and the adjacent wall of the casing.

The chuck jaws 37 are moved inwardly and outwardly by a bevel ring gear 43 which meshes with the pinions 40. A spur ring gear 44 is rigidly secured to the bevel ring gear and the ring gears 10 are oscillated by a rack bar 45 which meshes with the spur ring gear. It will be seen that oscillation of the ring gears will effect radial movements of the chuck jaws to engage and release a pipe 46. The ring gears 43 and 44 are rotatably supported 15 upon a hub-like portion of an end plate 47, of the chuck body portion 38 of the casing 32.

The rack bar 45 has pivotal connection with a piston rod 48 which extends into a cylinder 49 and has a suitable piston, so that when fluid 20 pressure is admitted to the ends of the cylinder alternately, the rack bar will be reciprocated. Suitable ports 50 and 51 (Fig. 6) are provided for admitting and exhausting fluid pressure into the ends of the cylinder 49. A manually operated 25 valve 52 is provided for controlling flow of fluid through the ports 50 and 51. When the pipe 46 is placed between chuck jaws 37, preliminary to threading, the valve 52 is operated to effect downward movement of the rack bar 45 to cause 30 rotation of the pinions 40 and closing movement of the chuck jaws 37, for the purpose of bringing the pipe into axial alignment with the threading tool 18. Operation of the valve 52 in reverse direction will, of course, effect retractive 35 movement of the rack bar 45 and opening of the chuck jaws.

The chuck 35 serves primarily to rigidly grip and hold the pipe against turning movement under the torque of the threading dies, and includes 40 jaws 54 which are mounted in the chuck housing 32 in substantially the same manner as that in which the chuck jaws 37 are mounted in the chuck body 38. The chuck jaws 54 are operated by a rack bar 56 in the same manner 45 as the chuck jaws 37 are operated by the rack bar 45. The chuck body 35 is supported by hanger bolts 63 and springs 64 that are in turn supported upon bridge plates 65 which are secured to the upper edge of the casing 32.

50 The rack bar 56 is operated from a piston and cylinder 68 which is controlled by a hand-operated valve 69 (Figs. 1 and 3) the operation being the same as described in connection with the rack bar 45 and the piston and cylinder construction 49. Fluid pressure for the cylinders at 49 and 68 may be generated by a motor 70 and a compressor 71 driven thereby; flow of fluid from the compressor to the pistons being controlled by the valves 52 and 69, as heretofore explained.

55 The provision of the aligning chuck 36 is of particular utility because the chuck jaws 37 are smooth faced and do not bite into the pipes as do the usual holding jaws such as the jaws 54. The peripheries of pipes are not usually of uniform hardness, and the teeth of the respective holding jaws 54 will, therefore, not all bite into or indent the pipe to the same depth. There is consequently a tendency toward slight misalignment of the pipe by the usual toothed holding jaws, 60 which danger is avoided where smooth faced aligning jaws, such as 37, are employed to prevent such misalignment.

65 As heretofore stated, the chuck carriage 33 is mounted upon the slideways 34 for movement toward and from the threading tool. Reciproca-

tion of the carriage is mechanically effected by a feed screw 73 which advances the carriage rapidly until the front end of the pipe is in position adjacent to the threading tool. A feed screw 74 thereafter advances the chuck carriage slowly 5 while the threading operation is being performed. The feed screw 74 is journaled at 75 and 76 in the lower portion of the housing 11 and extends to the opposite end of the base 10, as shown more clearly in Figs. 1, 11 and 12, where its opposite end is supported in a bearing 77. The feed screw 73 is similarly supported in bearings 78 and 79, Figs. 10 and 12.

The feed screws are driven from the ring gear 30, through a ring gear 80 that is mounted upon 15 the rotating sleeve member 13 and meshes with a gear wheel 81, the gear wheel 81 being mounted upon a shaft 82 which is supported in the lower part of the casing 11 and carries gear wheels 83, 84 and 85. The high-speed shaft 73 carries 20 change-speed gear wheels 86 and 87 which are selectively shiftable into engagement with the gear wheels 83 and 84 respectively. The preliminary feeding or advancement of the pipe to the threading tool may be faster where the pipe 25 is of relatively light weight, in which case the gear wheel 86 will be brought into engagement with the gear wheel 83. For slower advancing speeds for heavier pipe, the gear wheel 87 will 30 be brought into engagement with the gear wheel 84. The gear wheels 86 and 87 are manually operated by shifting fork 88, from a lever or pedal 89 (Fig. 10).

The slow feed shaft 74 is provided with change-speed gears 90, 91, 92 and 93 which are keyed 35 thereto, and which may be selectively engaged by change-speed pinions 94, 95, 96 and 97 respectively. These pinions are slidably mounted upon a counter-shaft 98 and are shiftable thereon by means of shifting forks 99 and 100. The 40 counter-shaft 98 carries a gear wheel 101 which meshes with the gear wheel 85. The change-speed gears just referred to are utilized to effect various rates of advancing movement of the pipe 45 into the threading tool, in accordance with the pitch of thread being cut on the pipe. In other words, if a thread of very small pitch is being cut, the pinion 97 will be brought into engagement with the gear wheel 93, and for larger pitch threads the pinion 94 will be brought into 50 driving engagement with the gear wheel 90, etc.

The high-speed feed shaft 73 has two wide pitch helical threads reversely arranged with respect to one another, one thread being employed when advancing the chuck carriage and the other thread being utilized to effect retractive movement thereof. A cylindrical nut 103 has engagement with the advancing thread of the shaft 73 and is positioned between the clutch or gripping members 104 (Figs. 12 and 13). The nut 103 60 is held against movement in one axial direction longitudinally of the carriage by a flange 105 that is formed integrally with the nut and engages a thrust bearing 106 that abuts against a plate 107 which is rigidly mounted in the carriage. Movement of the nut 103 in the opposite direction is prevented by reason of its abutment with a nut 108 that is similarly formed and mounted, and engages the reverse thread of the shaft 73.

65 When the nut 103 is held against rotative movement, rotation of the shaft 73 will cause the chuck carriage to advance rapidly toward the threading tool. The gripping jaws 104 for preventing rotation of the nut 103, are operated by 70 75

a shaft 110 that has threaded engagement with swivel nuts 111 (Fig. 13) which are oppositely threaded. When the shaft 110 is rotated in one direction, the gripping jaws 104 which are connected at their lower ends by a link 112 will be drawn into tight engagement with the nut 103. Turning of the shaft 110 in the opposite direction will, of course, cause release of the nut. The shaft 110 is journaled in bearing bushings such as 114, formed in the carriage 33. A hand lever 115 is secured to one end of the shaft 110.

The shaft 110, at its other end, has geared connection at 116 with a shaft 117 which extends parallel to the shaft 110, and through mechanism such as that shown in Fig. 13, controls a clutch, or gripping jaws, 118 for the nut 108. When the lever 115 is turned in one direction, the clutch members 104 are drawn together, and the clutch members 118 released, while when turned in the opposite direction, the clutch members 104 will be released and the clutch members 118 caused to engage the nut 108. In the latter instance, the chuck carriage will be retracted quickly at the completion of a threading operation. The clutch lever 115 has a neutral position, as shown in Fig. 7, wherein the clutches 104 and 118 are both out of gripping engagement with their respective nuts.

A divided nut 120 is arranged to be brought into cooperative engagement with the thread of the slow-feed shaft 74 when the carriage is in advanced position with the pipe adjacent to the threading tool and the advancing nut 103 released, (Figs. 12 and 14). Engagement and disengagement of the nut 120 with the shaft 74 is effected by a screw shaft 121 that has reversely threaded engagement with the respective halves of the nut 120. The halves of the nut 120 are mounted upon rods 122 which are supported in a frame 123 suitably secured within the carriage 33. The shaft 121 is operated by a hand lever 124.

The lever 115 is provided with a gear sector 125 whose periphery is grooved rearwardly of its teeth, to form a flange 126 at its rear face, as shown in Figs. 7 and 12. The flange has a slot 127 cut therethrough into which may enter a flange 128 formed on a segmental extension carried by the lever 124, when the parts are in the position shown in Fig. 7. As above explained, the lever 115 in Fig. 7 is shown in its neutral position with the high speed nuts of the shaft 73 released. At this time, the lever 124 can be swung clockwise to bring the slow-feed nut 120 into engagement with its shaft 74. The lever 115 is, therefore, locked against movement while the lever 124 is in its operative position. On the other hand, when the lever 124 is in its released position, as shown in Fig. 7, the lever 115 can be turned to effect either advancing or retractive movements of the chuck carriage. In either of these positions, the slot 127 will be out of registry with the flange 128 of the lever 124, and the lever 124 is, therefore, positively maintained in its released position.

The rapid advancing movement of the chuck carriage is automatically limited by the gear sector 125 operating upon a rack bar 130 which is slidably mounted on the chuck carriage, and which meshes with a rack pinion 131 that in turn engages a slidably mounted rack bar 132 (Figs. 7 and 12). When the lever 115 is turned in a counter-clockwise direction to effect rapid advance movement of the chuck carriage, the rack bar 130 will be shifted rearwardly to rotate the

pinion 131 and push the rod 132 to the left. The shaft of the pinion 131 is provided with a crank-like extension or arm 133, which carries a roller 134. By the movement just referred to, the crank 133 is turned in a counter-clockwise direction to the position shown in dotted lines in Fig. 7.

As the chuck carriage advances, it carries with it the rack bars 130 and 132. During this advancing movement, the roller 134 will be brought into engagement with a camming member 135 which is rigidly mounted upon the base of the machine. This cam tilts the crank 133 in a clockwise direction, to effect clockwise rotation of the rack pinion 131 and consequent shifting of the rack bar 130 to the left, with the result that the lever 115 is turned in a clockwise direction a distance sufficient to effect release of the feed nut 103, and thus automatically bring the carriage to a stop. The lever 124 can then be operated to effect slow advance movement of the carriage as above described.

At the completion of a threading operation, the lever 124 will be swung to its released position, the threading tools disengaged from the pipe, and the lever 115 then swung to bring the retracting clutch 118 into gripping engagement with the nut 108, to effect rapid retractive movement of the chuck carriage. During retraction movement of the chuck carriage, the rack bars 130 and 132 will be carried rearwardly until a nut 138 on the forward end of the bar 132 engages a stop 139, whereupon continued rearward movement of the carriage will cause the pinion 133 to rotate on the rack bar 132 and such rotative movement will effect movement of the rack bar 130 rearwardly, thus rocking the gear segment 125 to bring the lever 115 to neutral position, and thereby automatically stopping rearward travel of the carriage.

If desired, the chuck carriage can be manually advanced when the levers 115 and 124 are in neutral positions, by means of a hand lever 140, that operates a pawl and ratchet mechanism 141 for rotating a shaft 142 (Figs. 7 and 9). The ratchet wheel is loosely mounted on the shaft 142 and is normally held in driving engagement with a clutch disc 143 by a spring 144. The clutch disc 143 is rigidly secured to the shaft, and the shaft carries a pinion 145 that meshes with a gear wheel 146 which is mounted on a shaft 147 that carries a rack pinion 148. The rack pinion 148 meshes with a rack bar 149 that is secured to the under side of one of the stationary guide rails 34. It will be seen that when the lever 140 is oscillated, the chuck carriage will be gradually advanced along the track slide or guideways 34.

It is important that the manually operated lever 140 be automatically declutched when the automatic feeding and retracting mechanisms are in operation. To this end I provide on the rack bar 130 a reduced section at 150 which, when the lever 115 is in neutral position, will lie behind a lever arm 151 which is fastened on a rock shaft 152. The rock shaft carries a clutch fork 153 whose fingers engage the inner face of a disc 154. In the position of the parts shown in Figs. 7, 9 and 12, the reduced portion 150 is behind the lever 151 with the result that the spring 144 is operative to maintain driving engagement of the clutch surfaces between the ratchet wheel and the clutch disc 143. When the lever 115 is shifted to effect advance or retractive movement of the chuck carriage, the rack bar 130 is, of course, shifted and the lever 151

rocked to force the clutch fork 153 against the wearing disc 154, thereby forcing the ratchet wheel 141 away from the clutch disc 143, against the pressure of the spring 144. The carriage will then be moved independently of the hand lever 140.

In order that a pipe to be threaded can readily be positioned in the chuck carriage with its forward end projecting a proper distance from the carriage, I provide a gauge stop 160 (Figs. 1, 2 and 4) that is secured to a rod 161. At its one end, the rod 161 is rigidly secured against endwise movement, but rotatably supported in a bracket 162 that is formed on the casing 32, and at its other end, the rod 161 is slidably supported in a bracket 163 that is carried by the casing 11. The rod 161 carries an arm 164 which is provided with a cam roller 165 that cooperates with a cam track 166 of a bracket 167 which is secured to the casing 11. It will be seen that when the lever 115 is moved to cause rapid advance movement of the carriage 33, the rod 161 will be moved therewith, causing the roller 165 to move along the cam track 166 and rock the shaft 161. Rocking of the shaft 161 causes the gauge stop 160 to be raised to the position as shown by the dotted lines in Fig. 4, in which position it will be above the threading head that projects forwardly from the housing 11, so that continued advancing movement of the chuck carriage can be effected without interference of the gauge 160 with the threading devices. During withdrawal movement of the carriage 33, after a threading operation, the bar 161 will also be drawn back, so that the gauge arm 160 will fall in front of the threaded end of the pipe and thus be in position to serve as a positioning stop when another pipe is inserted into the chuck apparatus.

40 I claim as my invention:

1. The combination with threading die mechanism for pipes and the like, of a chuck carriage, a wide-pitch screw and nut device for moving the carriage toward and from the die mechanism at a rapid rate, a smaller pitch screw and nut device for advancing the carriage at a slower rate, a rack bar mounted on a stationary support for longitudinal movement thereon, a rack bar carried by and shiftable longitudinally of the carriage, said bars being disposed parallel to the path of carriage movement, a pinion meshing with the rack bars and journaled in the carriage, a lever on the carriage movable in opposite directions from a neutral position to selectively effect forward and rearward driving engagement between the wide-pitch screw device and the carriage, a connection between said lever and the second-named rack bar whereby the bar is shifted longitudinally when the lever is moved and whereby the lever is moved through movement imparted to said bar by the pinion, means for imparting rotative movement to the pinion at a predetermined advanced position of the carriage, for shifting the lever to neutral position, a stop device for limiting rearward movement of the first-named rack bar whereby the pinion is rotated to effect movement of the lever to neutral position at a predetermined point in the rearward travel of the carriage, a lever on the carriage movable to effect driving engagement between the smaller pitch screw device and the carriage, and means for preventing operation of either of said levers when the other lever is in operative position.

2. The combination with threading die mech-

anism for pipes and the like, of a chuck carriage, a wide-pitch screw and nut device for moving the carriage toward and from the die mechanism at a rapid rate, a smaller pitch screw and nut device for advancing the carriage at a slower rate, a rack bar mounted on a stationary support for longitudinal movement thereon, a rack bar carried by and shiftable longitudinally of the carriage, said bars being disposed parallel to the path of carriage movement, a pinion meshing with the rack bars and journaled in the carriage, a lever on the carriage movable in opposite directions from a neutral position, to selectively effect forward and rearward driving engagement between the wide-pitch screw device and the carriage, a connection between said lever and the second-named rack bar whereby the bar is shifted longitudinally when the lever is moved and whereby the lever is moved through movement imparted to said bar by the pinion, means for imparting rotative movement to the pinion at a predetermined advanced position of the carriage, for shifting the lever to neutral position, a stop device for limiting rearward movement of the first-named rack bar whereby the pinion is rotated to effect movement of the lever to neutral position at a predetermined point in the rearward travel of the carriage, a lever on the carriage movable to effect driving engagement between the smaller pitch screw device and the carriage, a lever-actuated device for manually advancing the carriage, and means for disconnecting the last-named lever from the carriage when the first-named lever is in operative position.

3. The combination with threading die mechanism for pipes and the like, of a chuck carriage, a wide-pitch screw and nut device for moving the carriage toward and from the die mechanism at a rapid rate, a smaller pitch screw and nut device for advancing the carriage at a slower rate, a rack bar mounted on a stationary support for longitudinal movement thereon, a rack bar carried by and shiftable longitudinally of the carriage, said bars being disposed parallel to the path of carriage movement, a pinion meshing with the rack bars and journaled in the carriage, a lever on the carriage movable in opposite directions from a neutral position, to selectively effect forward and rearward driving engagement between the wide-pitch screw device and the carriage, a connection between said lever and the second-named rack bar whereby the bar is shifted longitudinally when the lever is moved and whereby the lever is moved through movement imparted to said bar by the pinion, means for imparting rotative movement to the pinion at a predetermined advanced position of the carriage, for shifting the lever to neutral position, a stop device for limiting rearward movement of the first-named rack bar whereby the pinion is rotated to effect movement of the lever to neutral position at a predetermined point in the rearward travel of the carriage, a lever on the carriage movable to effect driving engagement between the smaller pitch screw device and the carriage, a lever-actuated device for manually advancing the carriage, and means for preventing operation of the second-named lever when the first-named lever is in operative position, and means for disconnecting the said lever-actuated device from the carriage when the first-named lever is in operative position.

4. The combination with thread die mechanisms for pipes and the like, of a chuck carriage, a wide-pitch screw and nut device for moving the

carriage toward and from the die mechanism at a rapid rate, means for advancing the carriage at a slower rate, a rack bar mounted on a stationary support for longitudinal movement thereon, a 5 rack bar carried by and shiftable longitudinally of the carriage, said bars being disposed parallel to the path of carriage movement, a pinion meshing with the rack bars and journaled in the carriage, a lever on the carriage movable in opposite directions from a neutral position, to selectively effect forward and rearward driving engagement between the wide-pitch screw device and the carriage, a connection between said lever and the second-named rack bar whereby the bar is shifted 10 longitudinally when the lever is moved and where-

by the lever is moved through movement imparted to said bar by the pinion, means for imparting rotative movement to the pinion at a predetermined advanced position of the carriage, for shifting the lever to neutral position, a stop device for limiting rearward movement of the first-named rack bar whereby the pinion is rotated to effect movement of the lever to neutral position at a predetermined point in the rearward travel of the carriage, a lever-actuated device for 15 manually advancing the carriage, and means for disconnecting the said lever-actuated device from the carriage when the first-named lever is in operative position.

EDWARD J. PROTIN.

15
